LUMINAIRE ASSEMBLY

Frank Van Steenhoven, Newark, Ohio, assignor to Holophane Company, Inc., New York, N.Y., a corporation of Delaware

Filed July 26, 1963, Ser. No. 297,895

5 Claims. (Cl. 240—11.4)

The present invention relates to lighting fixtures and in particular to integrally ballasted mercury vapor luminaires.

The presently accepted practice for the installation of mercury vapor luminaires includes, in general, two steps, after the ballast assembly and luminaire have each been purchased separately. The ballast assembly in its individual container is mounted to a ceiling or a structural member, and the conduit is installed leading from the ballast assembly to the point where the luminaire is to be positioned. The electrical wiring from the secondary of the ballast assembly is then pulled through the conduit and connected to the lamp socket on the luminaire. It is then necessary to remove the socket from the luminaire, connect the wiring from the ballast secondary to the socket, and re-install the wired socket to the luminaire. Due to the present day high labor costs, in many instances dual installation of the type mentioned above is equal to or sometimes even greater than the cost of the luminaire.

Accordingly, it is an object of this invention to simplify the installation of mercury vapor luminaires and their corresponding ballast assemblies.

Another object of this invention is to reduce the cost of such installation.

It is also an object of the present invention to provide an integrally ballasted mercury vapor luminaire.

Still another object of the present invention is to provide improved ballast assemblies.

Other and further objects of this invention will be apparent from the following description and claims and may be understood by reference to the accompanying drawings, which, by way of illustration, show preferred embodiments of the invention and what is now considered to be the best mode of applying the principles thereof.

In the present invention a potting compound is prepared and poured into the ballast assembly housing containing the electrical components and wires, at the place of manufacture. Thus, the electrical components and wires, excluding the ends of each wire which connect to the power supply leads and to the bulb socket of the luminaire, are conveniently encapsulated. The compound poured in and around the electrical components and wires serves to bond them in the capsule. The top of the luminaire assembly is connected to the bottom of the ballast assembly by any suitable means. Wires leading from the secondary of the ballast are detachably secured to the bulb socket in the luminaire. The luminaire assembly and the ballast assembly are positioned such that the socket for the luminaire extends to the bottom of the ballast assembly, thereby affording a convenient means for connecting the leads from the secondary of the ballast to the socket.

The ballast assembly includes a conduit adapter and supply wire chute and captive cover plate positioned over an access hole. The combination of the adjustable conduit adapter and access hole provides a convenient means for connecting electrical supply wires to the ends of the primary of the ballast.

For other objects and a better understanding of this invention reference may be had to the following detailed description taken in connection with the accompanying drawings, in which:

FIG. 1 is an elevational view of the lighting fixture assembly of this invention, partially broken away.

2

FIG. 2 is a view partially in section taken along line 2—2 of FIGURE 1.

FIG. 3 is an elevational view, partially in section, of the top portion of the ballast assembly of this invention.

5 FIG. 4 is a top view partially in section and looking down into the ballast housing with the cover removed and taken substantially along lines 4—4 of FIG. 3.

10 Referring now to the drawings, wherein similar reference numerals indicate corresponding parts throughout the several views, 10 represents the lighting fixture assembly, substantially as shown.

15 As shown in FIG. 1, the lighting fixture assembly 10 includes a reflector 12 connected to a yoke assembly 14. The yoke assembly includes two opposing plates, each plate including two L-shaped members 16 and horizontal legs 18. Reflector 12 is connected to yoke assembly 14 through opposing connector assemblies 20. These assemblies each include generally U-shaped brackets 22 pivotally mounted at an end on respective rods 24 secured 20 between horizontal legs 18 of the opposing plates of the yoke assembly. Pins 26 connected to collar 28 of reflector 12 or reflector support, as the case may be, engage U-shaped brackets 22. The socket 30, extending downwardly within reflector 12, is connected to ballast housing 32 by any suitable means. The housing 32 is constructed of cast aluminum, in this embodiment, to take advantage of the strength and maximum heat transfer of aluminum.

25 Housing 32 is secured to yoke assembly 14 by any suitable means. Within the top portion 34 of housing 32 a wiring chute 36 is secured to the inside of the top portion by self tapping screws 38. The wiring chute 36, as seen more clearly from FIG. 4, includes sides 40 and runway 42. Chute 36 is set at an angle inclined from the horizontal, as viewed in FIG. 2. A grounding lug 44 30 is connected to the bottom of runway 42 by a self tapping screw 46. A wire lead opening 48 is situated near the top of the inclined wiring chute 36 to provide the passage therethrough of electrical leads 68. A pivotally supported access cover 50 is hinged to the top portion 34 35 of housing 32, as shown in FIG. 2, by a round head screw 52. The end 54 of round head screw 52 is swaged to prevent the screw, and necessarily the access cover from falling off the housing and perhaps becoming lost, particularly during shipment of the fixture. As best seen 40 from FIG. 3 the access cover 50 may be rotated, after round head screw 52 has been loosened sufficiently, to the open position shown. Rotating the access cover to the open position provides a convenient means by which an electrician may complete the circuit connection, to 45 be described more fully hereinbelow.

50 A top cover 56 is secured to housing 32 by lock screws 58. A rotatable conduit adapter 60 is secured to top cover 56 by lock nut 62. The conduit adapter and lock nut combine to provide a convenient means of installation. The lock nut is made finger tight at the place of manufacture to permit an installation electrician to loosen the lock nut, while holding housing 32, and then screw the conduit adapter onto a supply conduit (now shown). The lock nut may be tightened after the assembly has been properly attached and oriented in the position desired.

55 The ballast components, capacitors 64 and transformer 66 are inserted at the place of manufacture within housing 32. Electrical leads 68 and 70 extend from the ballast components through openings 48 and 72 respectively. Leads 72 are secured to quick disconnect lugs 74 which are in turn electrically connected to socket 30. The portion of leads 68 which extend through openings 48 are left loosely hanging on wiring chute 36. 60 When the ballast components and their electrical leads have been installed at the place of manufacture they

are subsequently encapsulated with an asphalt potting compound 76. By encapsulating the ballast components they are made dust, bug and moisture proof, thereby substantially increasing their useful life. In addition, the compound serves to efficiently remove heat from the components to the housing 32 where it is quickly dissipated in the ambient atmosphere.

When the pre-wired units are received at the place of installation it is merely necessary for the electrician to take the electrical supply leads 78 and connect them to leads 68 by conventional connector elements 80. Grounding wire 82 is also easily connected to grounding lug 44. To accomplish the foregoing, the electrician need only loosen screw 52 and rotate the access cover 180° to provide him with an opening from which he may easily pull the wires, which have been guided to access opening 84 by the construction of chute 36. It is then a simple matter, after the connections have been made, to push the connected leads back into the wiring chute, swing the access cover shut, and securely lock it in place by tightening screw 52. The wiring chute thus obviates the necessity of fishing or groping for wires within the housing, as required in previous units. In addition, the placement of the ballast housing above the reflector permits continuance of the vented open top reflector. The resulting "chimney" action reduces maintenance by helping to keep the reflector free from dust.

While various embodiments of the invention have been shown and described in detail to illustrate the application of the inventive principles, it should be understood that the invention may be embodied otherwise without departing from such principles, and the invention should not be limited except as set forth in the following claims.

I claim:

1. In a lighting fixture including a luminaire supporting member, an electrical socket and a ballast assembly, said ballast assembly being secured to said socket and supporting member, the improvement comprising a housing having side walls exposed at their outer surfaces to the atmosphere and having an access opening therethrough, a ballast circuit within said housing, the output of said ballast circuit being electrically connected to said socket, and the ends of the input conductors of said ballast circuit being situated adjacent said access opening, conduit means in said housing for receiving the conductors of an external circuit, said conduit means being spaced from said access opening and sloping towards said access opening for guiding the conductors of the external circuit adjacent said access opening for connection to the input conductors of said ballast circuit.

2. In the lighting fixture of claim 1, wherein said conduit means comprises a portion externally of said housing, said portion including means independently movable for securing said ballast housing to an external

conduit carrying the conductors of the external circuit.

3. In the lighting fixture of claim 1, wherein said ballast circuit is mounted within said housing at one end thereof and said access opening, said conduit means and said means for guiding the conductor of the external circuit are mounted at the other end of said housing, said conduit means being spaced from said access opening, said guiding means comprising a chute sloping from said conduit means to said access opening, said chute being formed with access means for accommodating the ends of the input conductors of said ballast circuit.

4. A lighting fixture comprising a luminaire supporting member, an electrical socket and a ballast assembly, said ballast assembly being secured to said socket and supporting member, and comprising a housing having an access portion and a ballast circuit within said housing, the output of said circuit being electrically connected to said socket, and the ends of the input conductors of said circuit being situated in said access portion, and means enabling the introduction of the conductors of an external circuit into said access portion, said access portion including an aperture in said housing and a runway sloping towards said aperture, said means for introducing includes a cover detachably secured to the top of said housing, and means for securing said cover to an electrical conduit.

5. A lighting fixture comprising a luminaire supporting member, an electrical socket and a ballast assembly, said ballast assembly being secured to said socket and supporting member, and comprising a housing having an access portion and a ballast circuit within said housing, the output of said circuit being electrically connected to said socket, and the ends of the input conductors of said circuit being situated in said access portion, and means enabling the introduction of the conductors of an external circuit into said access portion, said access portion including an aperture in said housing and a runway sloping towards said aperture, said means for introducing includes a cover detachably secured to the top of said housing, means for securing said cover to an electrical conduit, and said components of said ballast circuit are encapsulated within said housing.
